PIT RAISER

David E. Mulholland, Reading, Pa.

Application December 30, 1947, Serial No. 794,581

9 Claims. (Cl. 153—48)

1

This invention pertains to a machine for and method of removing pits in a surface of metal sheets.

In the course of manufacture of stainless steel sheets, voids are at times developed in, at or adjacent to a surface of a sheet and subsequent polishing operations disclose the presence of such voids, commonly termed pits. Unless these pits are successfully removed the sheets are not acceptable to the trade or are not commercially saleable.

The principal object of the present invention is to provide an improved machine for and method of removing pits from the polished surfaces of metal sheets.

Another object of the invention is the provision of an improved means whereby pits in the surface of a metal sheet may be positively and definitely spotted preparatory to removing them.

A further object of the invention is the provision of a light mechanism or arrangement whereby pits in a surface of a metal sheet may be accurately aligned with a yieldable means operating on the other side of the sheet.

The above and numerous other objects will become apparent from the succeeding description considered together with the accompanying drawings wherein:

Figure 1 is a side elevational view of a machine for raising pits in surfaces of steel sheets.

Figure 2 is a horizontal sectional view taken along the lines 2—2 of Figure 1, looking in the direction of the arrows.

Figure 3 is a side elevational view taken along the lines 3—3 of Figure 2, looking in the direction of the arrows.

Figure 4 is a vertical sectional view taken along the lines 4—4 of Figure 2, looking in the direction of the arrows.

Figure 5 is an end elevational view taken along the lines 5—5 of Figure 1, looking in the direction of the arrows.

Figure 6 is a sectional view taken along the lines 6—6 of Figure 5, looking in the direction of the arrows.

Referring now in detail to the drawings, wherein like reference characters indicate like parts, the numeral 1 is employed to designate, in a somewhat general manner, an exemplified form of a machine for removing pits and the like from a metal sheet. The machine generally comprises a U-shaped casting or frame 2 disposed on its side and having an upper jaw 3 and a lower jaw 4 spaced a predetermined distance

2

from one another in a vertical direction. The bottom jaw may be formed with suitable pads 5 arranged to rest upon and be secured to any desirable foundation 6 to retain the frame in a fixed, steady position.

Forming an integral part of the forward or free end of the lower jaw is a lower cylinder 7 having disposed therein a lower ram 8 arranged for vertical movement with the related cylinder. 10 The lower ram has a shouldered portion 9 opposed from a shouldered ledge 10 formed in the cylinder and against which a coil spring 11 or any other type of resilient means may bear. The coil spring extends around a necked part 12 of the lower ram and is precompressed so that when the lower ram has completed its upward movement as will be discussed again in detail hereinafter, the coil spring will return the ram to its lower or starting position. Closing off the lower extremity of the cylinder 7 is a diaphragm 13 which is made of an oil resisting rubber stock and is clamped in place by a lower diaphragm cover plate 14. This cover plate is anchored to the cylinder and has axially thereof an inlet 15 15 to which there is attached a coupling 16 leading from a hydraulic system 17 of the machine. Accordingly, under certain operating conditions fluid pressure will be admitted to the lower area of the cylinder against the diaphragm to thus 20 urge the lower ram upwardly and when the fluid pressure is relieved the coil spring will urge the lower ram downwardly.

Suitably anchored to the upper end of the lower cylinder is an anvil plate support 18 which has 35 mounted thereon a bottom retainer ring 19. Disposed within the retainer ring is an anvil 20, stepped as at 21 with respect to the retainer ring and stepped as at 22 with respect to the anvil support plate to thus assure a firm interlock between these components. A piston 23 40 formed of yieldable or elastic or compressible material is firmly secured to the upper end of the lower ram through the medium of a piston holder 24 the latter of which is threadedly or 45 removably associated with the ram to be made a part thereof. The anvil 20 is fixed as recited above and thus affords a support for the sheet of metal (not shown) to be worked upon. The center of the anvil is provided with a chamber 50 into which an extrusion 25 of the piston extends. While the body portion of the piston may be conveniently made in the form of a cone the extension is desirably of cylindrical form with its diameter of about .0002 inch less than the diameter of the chamber. This relationship of ex-

tension and chamber prevents the yieldable material of the piston from being extruded and yet provides the necessary clearance thereabout to enable the piston to move slightly with respect to the anvil. The piston is of course removably secured in place as previously recited for the purpose of inspection and further to replace the piston if and when it becomes worn beyond a certain permissible degree.

Thus it will be now noted that a sheet of metal containing a pit or pits may be disposed between the jaws of the frame to be supported upon or by the anvil with the pit appearing in the surface of the sheet opposed to the surface thereof in contact with the anvil. A positioning of the pit in vertical alignment with the piston extension or anvil chamber will properly position the sheet of metal so that an upward movement of the lower ram will cause the piston extension to bear against the underside of the sheet and raise the pit for the complete removal thereof from the sheet.

The upper jaw of the frame carries an upper cylinder 26 forming an integral part thereof and containing therein an upper or holding ram 27. The upper extremity of the upper cylinder is covered by a flexible or yieldable diaphragm 28 which is clamped in place by an upper diaphragm cover 29, the latter of which, as will be understood, is removably secured to the cylinder by means of holding bolts 30 or the like. The primary purpose of the diaphragms in the upper and lower cylinders is to eliminate the use of packing around the rams past which leakage of the fluid under pressure might occur due to the exceedingly short stroke of each ram and the high pressure involved. Such leakage if permitted to occur would be objectionable and undesirable for purposes which are obvious.

The upper diaphragm cover has a central port to which a coupling 31 is attached for the introduction of fluid pressure to the exposed surface of the diaphragm for urging the upper ram downwardly from its illustrated position. The upper ram and cylinder are shouldered as at 32 presenting rests against which a coil spring 33 may bear. The coil spring, extending around the upper ram within the related cylinder is arranged to return the upper ram to its uppermost position upon a release of the fluid pressure from against the upper diaphragm.

Outstanding from the upper jaw at a location below the upper cylinder is a housing 34 formed by transversely spaced, angle-shaped, legs 35. Removably secured to each leg is a wedge-shaped guide plate 36 adjustably mounted on the leg so as to define a definite and fixed or adjustable area therebetween. Arranged to move vertically within the leg-guide plate defined area is a ram extension 37 having an upper horizontal wall 38 apertured for the relatively neat accommodation of a shaft 39 projecting downwardly from the upper ram. Locking means 40 is associated with the shaft to secure firmly the ram extension to the upper ram so that any vertical movement of the ram will be reflected in its extension.

The lower extremity of the ram extension has, forming a part thereof, longitudinally extending arms 41 spaced transversely of the frame and arranged to carry guide bars 42. A slide plate 43 is arranged with recesses or outwardly facing grooves 44 for the accommodation of the guide bars and this arrangement permits a longitudinal service movement of the slide plate along

a fixed predetermined path for the purpose to be hereinafter made apparent. The guide bars are adjustable both vertically and horizontally by means of bolts 45 so that a sliding fit may be effected between the guide bars and slide plate and the latter may be accurately moved along a designated path because this function is determinative of the accurate placing of pits in the path of the piston as will be brought out more in detail hereinafter. The slide plate is provided with a transversely extending undercut 46 into which there extends a top extremity of a die holder 47 with the latter retained in operable position by means of hanging guides 48. As viewed particularly in Figure 6 of the drawings at least one of the hanging guides is provided with an aperture 49 and on to the slide plate adjacent thereto there is secured a casing 50 which has projecting therethrough an index pin 51. This pin has, within the confines of the casing, a shoulder 52 which forms an abutment for a related extremity of a coil spring 53, and since the other end of the spring reacts against the casing the index pin will be urged, at all times, toward the die holder. Extending beyond the shoulder the pin forms a finger 54 arranged to extend into the hanging guide aperture and thus the die holder is locked against unwarranted or accidental displacement. Accordingly, this arrangement permits a transverse displacement of the die holder and its related components for the purpose of inspecting or exposing or repairing the piston.

Confined within the die holder is a seat 55 which functions as an accurately formed member against which a die cushion 56, also confined within the die holder, may react or be pressed against; the die cushion being formed of rubber, rubber compound or any yieldable material as will be clearly understood. Arranged within the die holder is a self-aligning shoe or die 57, made self-aligning because it bears directly against the die cushion and thus may vary somewhat within the holder as the die is urged toward the anvil as a result of a downward movement of the upper ram. This self-aligning feature insures a full flat bearing of the die or shoe against a sheet of metal to clamp the sheet against the anvil during a pit removing operation and eliminate the possibility of an edge of the die or shoe biting into the sheet. The die is shouldered as at 58 to accommodate a die retainer 59 which is removably secured to the die holder to thereby retain the die, cushion and seat within the holder. It will be here noted that the die extends downwardly beyond the limits of the die retainer so that the latter will not come in contact with the sheet of metal being worked on.

Spotting means has been incorporated in the machine to spot in a definite, accurate or sure manner a pit appearing in a sheet of metal. Unless the pit is positioned in true vertical alignment with the path of the piston it will be obvious that the ultimate function for which this machine was originally designed and invented may not be expeditiously or economically carried out. Accordingly, an exemplified structure which carries out parts of one of the objects of this invention is characterized by a light projector unit 60 mounted on the same end 51 of the slide plate as carries the index assembly and disposed to one side, in an outward direction, of the vertical limits of the die and anvil. The projector unit comprises a light source unit 62 having ex-

tending therefrom a hood 63 leading into a projecting device 64. Forming a part of the projector unit and spaced away from but in light ray alignment with the projecting device is a reflector 65 disposed at an angle and arranged to reflect a beam of light vertically. As previously indicated the slide plate is designed and carried so that it and its components may be moved from illustrated position inwardly or longitudinally of the machine for a predetermined distance. This distance is calculated to such a degree that when the slide bar is moved inwardly for the full extent of its permitted travel a beam of light coming from the reflector is concentrated on the piston or anvil chamber. Thus when the slide plate is moved fully inwardly of the machine and the light source is turned on a beam of light is concentrated on the piston or anvil chamber. At this time a sheet of metal is placed on the anvil with a pit appearing in the sheet properly positioned so that the beam of light will be focused on the pit. The sheet of metal is then held in this position and the slide plate is then returned to its normal or illustrated position at which time the two rams are activated so that the die or shoe will clamp or press the sheet of metal to or against the anvil and the piston will be urged upwardly against what might be termed the underside of the sheet to remove the pit appearing in the top side of the sheet of metal.

Means has been incorporated in the machine for moving the slide plate longitudinally of the machine or from one location to another for the purpose already recited. Toward the accomplishment of the above the upper jaw of the frame has a subjacent cylinder bracket 66 secured thereto. At one end of the cylinder brackets there is suitably mounted a double acting hydraulic cylinder 67 having projecting therefrom in a direction of the slide plate a piston rod 68 arranged to reciprocate through the action of or in response to fluid pressure supplied to the hydraulic cylinder by the feed lines 69; the latter of which it may be generally stated, derive their fluid under pressure from the same source that feeds the upper and lower rams; namely a pump and motor assembly indicated in Figure 1 only of the drawings by the reference character 10. The travel of the piston rod is arranged to equal the predetermined or required movement of the slide plate so that the ray of reflected light will be concentrated on the anvil chamber or piston when the slide plate is at its innermost location and the die is directly over the anvil when the slide plate is at its outermost location.

Forming a part of the cylinder bracket is a guide block 71 in which there is positioned a movable crosshead 72 coupled with the free or outer extremity of the cylinder rod to be moved as a unit therewith. Connecting the crosshead to the slide plate is a lever arm or link 73 which has one end thereof pivotally secured to the crosshead by a pin 74 and another end thereof pivotally attached to the slide plate by a pin 75. Accordingly any action of the hydraulic cylinder rod will be reflected in the slide plate. In actual practice the total movement or stroke of the upper ram is less than one-quarter of an inch to effect a clamping action by the die so that no additional provisions need be made in the horizontal slide plate-link-crosshead connection to compensate for the vertical upper ram movement.

Automatic means has been built into the machine for controlling the source of electrical

energy for the light source unit 62 so that the light will be turned on when the projector unit is over the anvil and turned off when the unit is spaced horizontally from the anvil. Toward the accomplishment of the above the guide block has mounted thereon switch means 76 arranged to remain stationary relative to the frame and connected to a source of electrical energy (not shown). This switch means is connected to the light unit 62 so that upon one tripping of the switch means the light unit will be energized and upon another tripping the light unit will be de-energized. Secured to the guide plate is an L-shaped switch bracket 77 having an arm 78 thereof projecting inwardly of the machine toward the guide block to overlie, in spaced relation, the switch means. The bracket arm is provided with longitudinally spaced webs 79 carrying adjustable bolts 80 and 80a which are in horizontal alignment with one another and with tripping buttons 81 of the switch means therebetween. When the slide plate is in the position illustrated, that places the die above the anvil, and bolt 80 has then contacted its related tripping button and the electrical energy is cut off from the light unit. When the slide plate is moved in a different or opposite direction to position the reflector plate directly over the piston or anvil chamber, the bolt 80a has contacted its related tripping button to supply electrical energy to the light unit. Thus the source of light is turned on or off as required for the successful operation of the machine.

From the above it will be noted that various changes and alterations may be made to the illustrated and described construction without departing from the spirit of this invention or scope of the appended claims.

I claim:

- 40 1. A machine for removing a pit and the like from a metal sheet, said machine comprising a member for supporting said metal sheet and having associated therewith an elastic means for engaging one side of said metal sheet, another member spaced from said first named member, said last named member being horizontally movably mounted on said machine and carrying a light from which a beam therefrom is adapted to be centered on the area directly over said elastic means for centering a pit directly over said elastic means, and an anvil carried by said last named member and adapted to be moved over said first named member.
- 45 2. A machine for removing a pit and the like from a metal sheet, said machine comprising a member having associated therewith an elastic means for engaging one side of said metal sheet for applying pressure to said sheet at an area directly opposed to said pit, another member spaced from and arranged to move toward said first named member for clamping said sheet between said members, said second named member being arranged to be moved horizontally and comprising a light and shoe, said light in one location being arranged to focus on an area directly over said elastic means for locating a pit, and said shoe in one location being arranged to bear upon said sheet including said pit.
- 50 3. A machine for removing a pit and the like from a metal sheet, said machine comprising a member, elastic means arranged to be forced out of said member for engaging one side of said metal sheet for applying pressure to said sheet at an area directly opposed to said pit, another member movable toward said first named mem-

ber, said second named member being movable transversely relative to said first named member and comprising a light adapted to direct a beam toward said elastic means to spot said pit, and a shoe carried by said second named member and adapted to be pressed against another side of said sheet at an area including said pit.

4. A machine for removing a pit and the like from a metal sheet, said machine comprising a member, elastic means arranged to be forced out of said member for engaging one side of said metal sheet for applying pressure to said sheet at an area directly opposed to said pit, another member movable toward said first named member, said second named member being movable transversely relative to said first named member and comprising a light adapted to direct a beam toward said elastic means to spot said pit, a shoe carried by said second named member and adapted to be pressed against another side of said sheet at an area including said pit, switch means for controlling said light, and means carried by said second named member arranged to operate said switch means.

5. A machine for removing a pit and the like from a metal sheet, said machine comprising an anvil having associated therewith an elastic means arranged to be urged therethrough for engaging one side of said metal sheet for applying pressure to said sheet at an area directly opposed to said pit, a slide plate spaced from and arranged to be moved toward said anvil, means for moving said slide plate transversely of said anvil, a light carried by said slide plate and arranged to have a beam therefrom focused on said elastic means for locating said pit directly in line with said elastic means, and a shoe carried by said slide plate arranged to be moved so as to bear against said plate at an area including said pit.

6. A machine for removing a pit and the like from a metal sheet, said machine comprising an anvil having associated therewith an elastic means arranged to be urged therethrough for engaging one side of said metal sheet for applying pressure to said sheet at an area directly opposed to said pit, a slide plate spaced from and arranged to be moved toward said anvil, means for moving said slide plate transversely of said anvil, a light carried by said slide plate and arranged to have a beam therefrom focused on said elastic means for locating said pit directly in line with said elastic means, a shoe carried by said slide plate arranged to be moved so as to bear against said plate at an area including said pit, switch means for controlling said light, and means carried by said slide plate for operating said switch means.

7. A machine for removing a pit and the like from a metal sheet, said machine comprising an anvil having associated therewith an elastic means arranged to be urged therethrough for

engaging one side of said metal sheet for applying pressure to said sheet at an area directly opposed to said pit, a slide plate spaced from and arranged to be moved toward said anvil, means pin-connected to said slide plate for moving the latter transversely of said anvil, a light source carried by said slide plate and arranged to have a beam reflected on said elastic means for locating said pit directly in line with said elastic means, and a shoe carried by said slide plate arranged to be moved so as to bear against said plate at an area including said pit.

8. A machine for removing a pit and the like from a metal sheet, said machine comprising an anvil having associated therewith an elastic means arranged to be urged therethrough for engaging one side of said metal sheet for applying pressure to said sheet at an area directly opposed to said pit, horizontally and vertically movable means spaced from said anvil, means for moving said movable means vertically toward and away from said anvil, means for moving said movable means parallel to said anvil, said movable means comprising a light source arranged to direct a beam reflected on said elastic means for locating said pit directly in line with said elastic means, and resiliently backed shoe means carried by said movable means and arranged to be pressed against said sheet at an area including said pit.

9. A machine for removing a pit and the like from a metal sheet, said machine comprising an anvil having associated therewith an elastic means arranged to be urged therethrough for engaging one side of said metal sheet for applying pressure to said sheet at an area directly opposed to said pit, horizontally and vertically movable means spaced from said anvil, means for moving said movable means toward and away from said anvil, a light reflector carried by said movable means, a light carried by said movable means and directed against said reflector to spot a pit directly in line with said elastic means, a resiliently backed shoe carried by said movable means and arranged to be pressed against said sheet at an area including said pit, switch means remote from said movable means for controlling said light, and means carried by said movable means arranged to control said switch means.
